UNITED STATES PATENT OFFICE

2,413,372

PROPELLER

Bernard J. Paulson, Waukesha, Wis.

Application May 24, 1944, Serial No. 537,146

5 Claims. (Cl. 170—156)

1

My invention relates to propellers, and more particularly to a type of propeller that is stamped out of a single piece of material, or molded from plastic materials in a single, integral unit, working on the large volume of the medium extending radially from the unit, instead of the conventional medium entering from the back or front of the unit.

The object of my invention is to provide a device of the character described, that can be used as a propeller or impeller, of high efficiency, thereby permitting a reduction in size over the conventional blade or vane type of propeller.

Another object of my invention is to provide a device that may be used for either air, vapor, liquid or any other medium; a device that increases the volume and velocity of the material to be drawn, actuating and causing a flow not only on the face of the propeller, but also on the peripheral outer area of the device, and providing, due to its contour, a supercharging effect, creating a cushion of dense air immediately behind the propeller, thereby providing a forward thrust by the air entering the front face of the propeller, and impinging against the dense cross currents immediately back of the propeller frontal area.

Another object of my invention is to provide a device that will produce a centripetal flow of high velocity current taken in at the ports on the circumferential periphery from the broad radial area extending therefrom, causing this flow of air or the like to be thrown cross-wise against the inside radius of the outer thrust ring, thereby building up a pushing or forward thrust force.

Still another object of my invention is to provide a device that will produce a low pressure area directly in front of the radial thrust ring, thereby producing an area of low resistance on the front face of the radial ring, so that the high pressure on the back side of the propeller will produce a high ratio of propulsion efficiency.

A still further object of my invention is to have the disc type of propeller act as a fly wheel to provide and sustain momentum for the engine in case of momentary stalling, also causing a sufficiently high revolutions per minute to provide propeller aid for the engine in a landing operation.

Still another object of my invention is to produce a device that need not revolve as fast as a blade type propeller which is a distinct advantage in some instances, and

Another object of my invention is to provide a propeller that produces a centripetal flow of

2

air taken in at the periphery of the disc, combining a centripetal intake of the medium with a powerful centrifugal discharge.

Other and further objects of my invention will become more apparent as the description proceeds when taken in conjunction with the drawings, in which:

Figure 1 is a front view of the face of a propeller illustrating the manner of staggering the louvres, acting as scoops on the front face and circumferential face of the device.

Figure 2 is a cross sectional fragmentary view of Figure 1, indicating by arrows the travel of air currents.

Figure 3 is a similar fragmentary cross sectional view of a similar type of propeller having a concave frontal face.

Figure 4 is a cross sectional view of a portion of the propeller, illustrating the manner in which the louvres are to be formed in which the intake has a radially formed lip, producing an inertia impact against the inner face of the canopy.

Figure 5 is a front view of the face of a propeller, showing a plurality of elongated louvres extending outward from the center to the periphery of the device and showing louvres disposed in alignment with one another on the circumferential face thereof, and

Figure 6 is a fragmentary cross sectional view of the device shown in Figure 5, showing the travel of the air currents indicated by arrows.

Similar characters of reference indicate corresponding parts throughout the several views, and referring now to the same, the character 19 shows a propeller comprising a single metal stamping, consisting of a drum type frontal face 11, a peripheral flange 12 and a convex radial thrust ring 13.

The face 11 and the flange 12 are provided with louvres 14 and 15 respectively. These louvres 14 and 15 are punched and extruded or embossed out of the material constituting the device, and arranged to provide an opening 16, facing the direction of revolution of the propeller itself and a canopy or shell 17. By referring to the Figure 4, it will be noted that the intake lip 18 is radially disposed at the opening 16 causing the flow of air, as shown by the arrow, to build up an inertia impact in its contact with the inner face 19 of the canopy 17. The canopy 17 is semi-cylindrical in contour and tapers off from the opening 16 to the face of the propeller. The opening 16 may be placed at any desired angle to conform with the volume of air to be "scooped" and the louvres 14 and 15 may be placed in staggered relation to one

another to permit the flow of air contacting the surface of the propeller, either at its face or flange between the louvres to be guided into the direct path of the louvres.

The thrust ring 13 of a convex contour is radially disposed without louvres and has a tendency to force the air outside of the periphery of the thrust ring backward, thereby forming an area of low resistance immediately adjacent the peripheral louvres or scoops 15 on the flange 12 of the propeller 10. The entire unit is mounted onto a suitable propeller shaft 20. In Figures 5 and 6, I show a modified form of the device having the louvres 21 elongated and extending outward from the shaft 20 in the direction of the flange 12. The louvres 22 on the radial flange are set at a pre-determined angle and are also elongated to correspond with the depth of the face of the flange. This places the louvres 22 in direct alignment with one another, instead of the staggered path of louvres 15 shown in Figure 1.

In operation, the air or the like enters the frontal ports 16 of the louvres 14 or 21. The air is actually scooped or cut by the peripheral edges of the combined louvres, and the number of louvres or scoops and their size will determine the cutting edge provided. With this arrangement, it is possible to obtain far more cutting edge to the propeller than is possible to obtain with a conventional type of blade propeller. As the air enters the ports 16 of the louvres or scoops, it is thrust upward by the lip 18 shown in Figure 4, against the inner surface 19 of the canopy 17, thereby producing an inertia impact causing a forward thrusting action. The area of this inner surface 19 is, of course, dependent on the length and taper of the canopy 17 and the propulsion produced is governed definitely by the design of the louvres.

The peripheral louvres 15 and 22 receive their air from the circumferential area of the propeller, and force it centripetally at high velocity across the inner area of the propeller at an appropriate angle to strike with maximum force against the inner surface 23 of the thrust ring 13. The inlet of the air through the louvres 15 and 16, produces a low resistance area immediately in front of the thrust ring 13, caused by the high velocity centripetal air stream as it passes directly in front of the ring, and the flow of air from the opposite side against the inner surface 23 of the thrust ring 13 changes to centrifugal force as it is deflected from the surface 23. This action also helps to produce a partial vacuum, or area of low resistance not only ahead of the thrust ring 13, but in the entire zone immediately behind the propeller, creating a central vortex induced by the tornado-like whirling action of conflicting air currents.

The air currents entering through the louvres 14 and 21, flowing at lower velocity than the cross currents due to the diameter of the propeller being greater at the flange 12, automatically merge with the radially induced cross currents and flow away from the center by centrifugal kinetic force against the inner surface 23 of the radial thrust ring 13.

In Figure 5, I show a plurality of radially depressed areas 24 disposed within the radial con-

tour of the thrust ring 13. This modification assists in breaking the steady stream or flow of air deflected rearward from the inside radial thrust ring, and assists in the agitation and mixing of the various air currents and their final unification in a dense discharge current, for the promotion of propulsion efficiency.

It is manifest to anyone familiar with the art, that a device as illustrated and described, applies to many uses, such as airplane propellers, 10 ventilating and air conditioning fans and blowers, high velocity super-chargers, material handling blowers, fluid drive impellers, mixers on homogenizing liquids or semi-solids and many 15 others, and while I have illustrated and described a specific structure and arrangement of elements constituting the device, I do not wish to be limited to these specific structures, but reserve the right to make such changes and configurations as stay 20 within the description and the scope of the appended claims.

What I claim and desire to obtain by Letters Patent in the United States is:

1. A device of the character described, comprising in combination an integral disc of annular contour provided with a flat face and a rearwardly extending flange on the periphery thereof, and a radially disposed thrust ring extending rearward from the depending edge of 25 said flange, a plurality of louvres cut into and extending outward from said face, said louvres spaced in radial alignment and in staggered relation to one another, a plurality of similar louvres on the peripheral flange also placed in staggered 30 relation to one another, the open end of said louvres facing the direction of revolution of said device.

2. A device of the character described in claim 1, in which the open end of said louvres are 40 angularly disposed with relation to the axial alignment of said device.

3. A device of the character described, comprising in combination an integral disc annular in contour, provided with a flat face and a rearwardly extending flange on the periphery thereof, a radially disposed thrust ring extending rearward from the extending circumferential 45 edge of said flange, a plurality of louvres cut into and embossed outward from the said face and flange, the said louvres having their open ends facing the direction of revolution of said device, the inwardly depending end at the open end disposed upward in a radial contour to direct the air entering said louvre against the inner 50 face of the canopy thereof.

4. A device as described in claim 3, in which the inner surface of said thrust ring is smooth to permit the air entering the louvres of said flange to be deflected rearward after being carried centripetally along the rear surface of said 55 face of the device.

5. A device as described in claim 3, in which the thrust ring is provided with concave indentations to provide convex surfaces to diffuse the air entering the louvres of said flange deflected rearward after being carried centripetally along the back surface of the face of the device.

BERNARD J. PAULSON.
